PROTECTION ROD SPRING

Harold Hoeber, South Dartmouth, Mass.; Barbara O. W. Hoeber and William T. Read as executors of said Harold Hoeber, deceased, assignors, by mesne assignments, to Hoosac Mills Corporation, Boston, Mass., a corporation of Massachusetts

Application December 8, 1945, Serial No. 633,729

2 Claims. (Cl. 139—346)

1

This invention relates to a loom, more particularly to the resilient means which is applied to the protection rod upon which the dagger is mounted.

The protection rod extends lengthwise of the lay of the loom and is usually mounted in a bearing adjacent either of its ends and also may have a center bearing. The dagger is carried by this protection rod while an arm extends from the rod up into operative relationship with the binder of the shuttle box so that if the shuttle is not in position in the box the dagger will not be raised and consequently the loom will bang off. In order to lower the dagger into a position so that the loom will bang off if the shuttle does not enter the box a spring is provided. This spring is usually in helical form and encircles the protection rod at substantially its center. It may be adjusted as to tension by a collar which may be rotated about the rod while one end is held fixed with reference to the lay. So long as the rod is in perfect axial alignment throughout its length this sort of spring may operate satisfactorily, but should the rod become somewhat out of axial alignment greater friction is then present in the bearings and considerable binding on the rod at the bearings occurs. When such a condition is present, greater spring tension is required and other difficulties are experienced, especially when the loom is operated at high speed.

One of the objects of this invention is to provide resilient action to move the dagger into position to bang off without this spring acting through the long axial length of the protection rod and thereby subjected to irregularities of friction which may develop between the protection rod and its bearings.

Another object of this invention is to apply resilient action at the location of the point of use of the resilient action so that this resilient action will be less distorted by friction which occurs in the rotation of the protection rod in its bearings.

Another object of this invention is to provide an arrangement so that the spring which acts on the protection rod may be removed without removing the protection rod from its mounting on the lay.

Another object is to provide spring action on the protecting mechanism which may utilize a resilient means which will not crystallize.

With these and other objects in view, the invention consists of certain novel features of construction, as will be more fully described and particularly pointed out in the appended claims.

In the accompanying drawings:

2

Fig. 1 is a sectional view illustrating a fragmental portion of a lay with the resilient means acting on a protecting mechanism in accordance with this invention;

5 Fig. 2 is a section on line 2—2 of Fig. 1;

Fig. 3 is a section on substantially line 3—3 of Fig. 1;

Fig. 4 is an elevation of a fragmental portion of a lay equipped with the modified form of resilient means;

Fig. 5 is a top plan view of the structure shown in Fig. 4.

In proceeding with this invention, I remove the coiled spring which usually encircles the protection rod which extends along the lay and apply a resilient means to the arm which extends upwardly from the protection rod to be operatively associated with the back binder of the shuttle box. In this way the spring acts through a greater leverage than heretofore and closer to the point of use of the pressure desired so that friction in the bearings of the rod will be relatively minor in effect upon the protecting mechanism.

With reference to the drawings, 10 designates 25 the lay having a reed 11 carried thereby with hand rail 12 which is secured in position by nut 13. A shuttle box is designated generally 14 and consists of a front wall 15 and a back wall 16 with a back binder 17 movable through the back wall 16 as set forth more fully in my companion application. The protection rod 18 is mounted in bearings 19 at either end of the lay and also in a center bearing of usual known form. This rod 18 extends upwardly as at 20 and has an arm 21 secured thereto which extends further upwardly and has adjustably mounted therein an abutment 22 which is threaded as at 23 and is held in position by nut 24. This abutment 22 is moved into engagement with the rear surface of the back binder 17 by resilient means designated generally 25 (see Fig. 1) which will be described in greater detail below. A dagger 26 is also carried by the protection rod 18 and is moved downwardly by the rocking of the rod through the spring means 25 to force the back binder inwardly. The protection rod stop designated generally 29 is provided with its leather cover 30, the stop being mounted by means of bolt 31 through the lay 10, the same being in a position to engage the dagger 26 so as to prevent its lifting too high. The picker stick is designated generally 32 and the check strap is designated 33, being mounted upon the check strap bracket 31 and movable through the friction members 34, 35, and 36. 55 When this dagger is in its lower position, which

occurs when the shuttle is out of the shuttle box 14, it will engage the lip 27 of the frog 28 to move this frog and cause the loom to bang off in a known manner.

The resilient means for applying pressure on the arm 21 which serves to follow the back binder 17 as it moves inwardly and to move the dagger into operating position when no shuttle is present in the box, consists of a bracket 40 having a bolt 41 extending through the portion 42 to 10 mount it adjacent bracket 31 and below the back of the shuttle box 14. This bracket is provided with a boss 43 in which there is a rod 44 mounted by means of nuts 45 on one side of the boss and 46 on the other side of the boss. This rod rotatably mounts an arm 47 at its outer end which is held against sliding off the end of the rod by a collar 48. This arm has a finger 49 which extends parallel to the axis of its hub which is mounted on the rod 44 and which upon swinging will engage arm 21 which is mounted on the protection rod portion 20. A spring 50 circles rod 44 and is fixed to the nut 45 at one end while the other end extends into the hub of the arm 47. This spring is given sufficient torsion 15 by rotation of the rod before the same is bound firmly into position by the nut 46 so as to cause the arm 47 to apply the desired pressure on the arm 21 of the protection rod.

In some cases instead of applying resilient pressure by means of a helically wound torsion spring upon the arm 21, I may mount a leaf spring 55 on the check strap bracket 31 carried by the lay 10 by means of a resilient plate 56 having an arcuate portion 57 engaging the lay while bolts 58 extend through the doubled back portion 59 of the spring and extend through the plate 56 into the lay. By the tightening up of these bolts more or less pressure may be applied to spring the plate 56 so as to firmly bind the 20 leaf spring in place. At the outer end of the spring 55 rests the protection rod finger 21 which has been heretofore described.

It is apparent that the above-described protection rod spring constructions could be applied to a loom having front binders if so desired.

I claim:

1. In a loom, a lay having a shuttle box at its end with a movable binder, a rockably mounted protection rod extending along the lay and having a dagger thereon movable therewith and an arm extending therefrom into engagement with said binder and responsive to movement of said binder by a shuttle entering said box to rock said protection rod and consequently said dagger, a stationary rod attached to said lay, a crank rockably mounted on said rod and extending into engagement with said arm, and a torsion spring acting throughout the entire operation of the lay for urging said crank into engagement with said arm.

2. In a loom as in claim 1 wherein a bracket 20 adjustably mounts said stationary rod on said lay.

HAROLD HOEBER.
